UNITED STATES PATENT OFFICE.

ALBERT ALFRED CARPER, OF CATONSVILLE, MARYLAND, ASSIGNOR, BY MESNE ASSIGNMENTS, TO LAURENCE C. STOUDENMIRE, OF BALTIMORE, MARYLAND.

BOTTLING-MACHINE.

1,258,187.

Specification of Letters Patent.

Patented Mar. 5, 1918.

Application filed August 27, 1914. Serial No. 858,936.

To all whom it may concern:

Be it known that I, ALBERT A. CARPER, a citizen of the United States, residing at Catonsville, Maryland, have invented certain new and useful Improvements in Bottling-Machines, of which the following is a specification.

This invention relates to bottling machines in which the bottles are filled and closures 10 are applied thereto, the closures used being of the crown type.

One object of my invention is to simplify the machine and at the same time increase its efficiency and particularly as regards 15 speed of operation.

One feature of my invention relates to the means for automatically supplying closures at proper times to the capping head, said means coöperating with an automatic pad 20 block for closing the cap port in the head. Other features will be clear from the following description.

In the accompanying drawings:

Figure 1 is a view of the upper portion of 25 the machine partly in section and partly in elevation.

Fig. 2 is a view of a portion of the filling tube in section, together with a spreader for the liquid to prevent foaming.

80 Figs. 2^a and 2^b are cross sectional views on lines 2^a—2^a and 2^b—2^b respectively of Fig. 2.

Fig. 3 is a detail sectional view of the syrup pump.

35 Fig. 4 is a plan view in diagrammatic form of the rotary capping head, cap feed, pad block for closing the cap port and associated parts.

Fig. 5 is a plan view of the parts shown 40 in Fig. 1 with parts in section.

Fig. 6 is a view of the entire machine partly in section and partly in elevation.

Figs. 7, 8, and 9 are details.

Fig. 10 is a plan view of part of the means 45 for moving the bottle carrier.

Fig. 11 is a detail view of a lever with the cams for operating it.

Fig. 12 is a detail view of part of the means for operating the bottle carrying 50 table.

Fig. 13 shows the bottles elevated to the syrup pump and filling and capping head by a single plunger.

In carrying out one part of my invention, 55 I employ a bottle receiving and capping

head 1 capable of having rotary reciprocating movement, said movement as an example being equal to about one-fifth of a revolution. While the head is shown as turning about its own axis the invention is not limited in this respect. This head has within it cap positioning devices consisting of lugs or shoulders 2, (dotted lines Fig. 1) against which the inner edge of the cap rests when it is moved thereagainst through the cap port 3 formed in the side of the head. These lugs are well known in the art, being shown at h^2 in patent of Carper granted December 26th, 1911, No. 1,012,984. The cap in this position overhangs the central bore of the head so that as the bottle is lifted for capping to the capping tool 4, the bottle head will first strike the overhanging edge of the cap, lift it from its positioning or retaining lugs and a spring finger 5 contained in the pad block 6 will project the cap over the bottle to be carried up thereby into the capping die which will apply the cap to the bottle in a manner well known. For feeding the caps to the head, said head is given the turning movement above mentioned to bring the cap port into registry with a cap feed chute 7 which directs the caps down from a hopper 8 to the head.

The head is mounted to turn in the frame of the machine at the bearing 9, said head having a lower flange 10 to bear against the lower side of the said bearing with an interposed liner 11, said head being retained in the said bearing by a collar 11' at the upper part of the head resting on the upper end of the bearing. The function of the pad block 6 is to seal the cap port against the escape of gas or liquid during the filling and capping operation and it is utilized to support the spring finger 5, which as above stated pushes the cap into position over the bottle.

For turning the head to effect the feed of the caps and for other purposes, hereinafter mentioned, various means may be provided, but in the particular construction shown, I employ a lever 12, pivotally mounted at 13, being fixed on a pin 13' mounted in brackets 14—15 of the main frame, said lever being swung at intervals from the full line position Fig. 4 to the dotted line position. In this movement the hook end 16 of the lever engages a roller or pin 17' on the head and turns the same so that the cap port will

be turned away from its position in which it registered with the pad block 6 to a position in registry with the cap chute 7 and immediately this occurs, the lowermost cap 5 will pass from the cap chute into the cap port, the weight of the column of caps in the chute being sufficient to do this and the cap fed in will seat itself against the lugs or positioning devices.

10 For the turning of the head, it is desirable to remove the pad block together with its projecting spring finger away from said head, to avoid obstructing the head's movement. While this may be done in various 15 ways in the particular construction shown, I employ the lever 12 as a carrier for the pad block so that as the lever 12 swings it will retract the pad block and spring finger from the head and turn the head into cap 20 receiving position.

After the head has received a cap it is moved back to its former position so that its port may be sealed liquid or gas tight by the pad block. This turning back of the 25 head or the advance of the pad block to seal the port is accomplished by the return movement of the lever 12, the hook end of said lever maintaining its engagement with the pin or roller on the head until the normal 30 position of said head is reached, the lever continuing its movement sufficiently after the hook has disengaged the roller to seat the pad block in firm sealing contact with the head about the cap port, the lever having a concentric surface 17 to bear on the roller and hold the head in normal position, while the finger 5 is moved against the cap 35 and the pad block is being seated at the cap port.

40 The cap chute remains stationary and the movement of the capping head may act as a cut off for the caps in the said chute, the lowermost cap resting against the side face of the head when this is turned with its 45 cap port away from registry with the chute, though I do not limit myself to the use of the head as a cut off for the caps.

During the filling of the bottle with the liquid which may be either still liquid or 50 gas charged it is necessary to seal the head not only at the cap port as above described but at the point where the bottle head seats itself into connection with the head in which the capping is done. This sealing is done 55 by a gasket 18 resting against an abutting ring 19 within the head, and held by a loose ring 19' which in turn is carried by a compressing ring 20. The function of this compressing ring is to compress the gasket so 60 that a liquid and gas tight joint will be formed between it and the bottle or between the gasket and the surrounding portion of the head. While this gasket compressor ring may be constructed, arranged and operated in various ways I mount it on the

lower end of the head by a coarse screw thread 21. This ring is prevented from turning but as the head turns the screw thread connection will lower and raise the compressor ring so that the gasket will be 70 allowed to relax *i.e.* upon lowering the ring, or it will be compressed upon the rise of the ring and thus contracted to make gas tight contact with the bottle when this is raised into engagement therewith. 75

The gasket compressor ring is held against turning by any suitable connection with the frame, as will be described hereinafter.

The lever 12 is operated by a two armed lever 12^x Figs. 5, 6, and 11, pivoted on the pin 13^x, the said lever having rollers thereon acted on by a cam member composed of the upper and lower portions 22, 23 on the upright shaft 24, which is suitably driven. One arm of the lever 12^x has a roller 12^a 85 lying above it to engage the upper cam portion, while the other arm has its roller 12^b engaging the lower cam portion.

The drawing, Fig. 1 shows the bottle in position for filling and the cap in position to 90 be dislodged by the upward movement of the bottle, after being filled, from the position shown, said cap when dislodged being projected over the bottle by the spring finger to be carried up by said bottle into the 95 die 4 for the capping operation. While the bottle is in the position shown it is filled with the water. Various means may be employed for delivering the liquid into the bottle, but in the particular construction 100 illustrated I employ a filling tube 25 passing through the cap seating plunger 25^x carried in the head and pressed downwardly by a spring 25'. This filling tube extends above the capping head and has a valved coupling 105 or head 26^x thereon with which connects the supply pipe 26^a for the liquid to be delivered into the bottle.

This coupling head has a hand operated cock 26 to regulate the supply and it has an 110 automatic valve 27 for determining the times of delivery of the fluid to the bottle. This valve seats at 27' to cut off the supply, being pressed onto its seat by the spring 28. It is opened by its rod 29 contacting with 115 the top of the head at 27^a when the filling tube is moved down to deliver the liquid into the bottle. The filling tube may be operated in various ways but as shown it is moved vertically by a friction clamp 30 120 which is split and pressed by a spring 31. This clamp engages frictionally a collar 33 screwed on the upper end of the filling tube.

The coupling carrying the valves as described is mounted on a bracket 36 slidable 125 vertically on the pin or rod 35. The clamp 30 is integral with a sleeve 34 slidable vertically on the pin 35 fixed to the frame in any suitable way.

The sleeve 34 is moved vertically by a 130

link 37 pivoted thereto and to a lever 38 which lever is pivoted to the frame at 39 and having a roller 38' entering a cam groove in a face wheel or cam 40 mounted on the shaft 41 suitably mounted in the frame.

The clamp 30 having frictional contact with the collar 33 is provided to permit the disconnection between said clamp and the filling tube, should the tube strike the bottle or meet with other obstructions when it is lowered.

If such disconnection occurs the operator can readily make the connection again by pressing the filling tube with its collar down into the friction clamp. This can be done when the clamp rises and lifts the tube by the collar.

With the use of a filling tube through which the liquid under pressure is introduced into the bottle it is desirable to prevent foaming of the liquid and I have provided means to this end. This may assume various forms but in the particular construction shown, this consists of a spreader in the form of a member 42 having a countersink 43 in its upper face against which the stream of liquid impinges. This member 42 is carried by a sleeve 43* which is slotted longitudinally at 44 at different points about the same so that the stream of liquid discharged from the filling tube upon striking the member having the countersink will be spread laterally and upwardly and will be broken up upon passing through the longitudinal slots in the surrounding sleeve with the result that the liquid will settle into the bottle without foaming. This liquid spreading member is located within the bottle and may be variously supported. In the particular construction shown it is carried by the filling tube at some distance below the discharge end *a* of said tube. This discharge end is contracted to deliver a thin stream of liquid. The spreading device may be variously connected to the filling tube but in the particular construction shown, I employ a hanger 45 attached to or connected with the tube. The upper end of the sleeve 43* is of larger diameter than the discharge end of the filling tube so that the stream of liquid which naturally spreads slightly after leaving the filling tube will be caught by the said sleeve. The distance from the discharge end *a* to the upper mouth of the sleeve 43* is such that the whole stream of liquid will be caught.

In order to secure a better separation between the oncoming stream of liquid and the liquid as spread by the spreading device I arrange a sleeve 46 within the sleeve 43* and preferably spaced apart from the slotted sleeve. The end of the sleeve 46 lies close to the countersunk face of the spreading member and the liquid as spread passes up outside of the inner sleeve thus keeping it sepa-

rate from the stream as discharged at *a* from the filling tube.

In machines of the type herein described means are provided for the escape of air and gas from the bottle to permit the entrance of the liquid and to thereby secure a rapid fill. While such means may be provided in various ways, in the particular construction shown I employ a venting valve 47 in a chamber 48 located alongside of the head 1 and connected thereto by a port 49. The valve is seated at 50 by a spring 52 and its stem 51 extends up through the housing 53 and above the same. Above the valve a port 54 leads to a needle valve box 55 Fig. 5 the passage through which is controlled by a needle valve 56 adjusted by a screw thread connection said valve being set by hand.

The final escape port 57 leads from this valve box. The vent valve is opened by the lever 38 bearing upon the upper end of the valve stem. This lever 38 therefore controls both the venting valve 47 and the water valve 27, but in the operation of these the water valve opens first then the venting valve. In closing, the vent valve closes first and then the water valve and by reason of this, the pressure is allowed to rise in the bottle just before the capping is done so that the bottle will be capped under a maximum pressure.

It is customary to supply to the bottle a certain amount of syrup. This may be done in different ways but in the particular form of machine shown in which the bottles are carried by a rotating table I supply the syrup at one station and the water at another. For supplying the syrup I use a pump comprising a chamber 58 suitably supported on the frame having within it a diaphragm 59 held to a plunger 59* by a screw and washer at 60. The syrup enters through a port 61 in a fixed frame part 62 forming an extension of the pump chamber 58 and sliding on the extension is a bottle receiving member 63. This member has two passages 64 and 65. To the former a conduit for syrup connects and when this passage registers with the port or passage 61 leading to the pump the syrup will flow up into the pump and raise the diaphragm until the adjustable stop 66 arrests further upward movement which thus determines the charge of syrup which the pump will contain to be delivered to the bottle. This inlet of syrup to the pump takes place when the sliding member is in its low position. Now when a bottle is raised its mouth enters the flaring bottle head receiver 67 and pushes the sliding member up to cut off the inlet of syrup to the pump and to bring the passage 65 in registry with the pump passage 61 and when this takes place the charge of syrup will pass from the pump through the passages 61 and 65 into the bottle. The bottle then moves down allowing the sliding member 63 to

move down also and bring its port 64 in registry with the passage 61 for the inflow of another charge of liquid to the pump. The bottle is raised to the syrup pump by 5 any suitable means, as by a plunger connected with the plunger 78.

The sliding member is arrested in its downward movement by the stop 63. The sliding member is subjected to frictional restraint by springs carried thereby pressing a friction plate or member 69 against the fixed extension 62 of the pump. After the bottle receives its syrup and has been lowered from the member 63 the bottle carrier 15 takes a forward step and brings the bottle beneath the head 1 for filling and capping upon the rise of the bottle at this station.

The rotating dial or carrier for the bottles may be variously arranged, constructed and 20 operated. In the particular construction shown the dial or carrier 70 has openings for receiving the bottles which rest on a platform 71 fixed to a standard or column 72 extending up from the main base 73. This 25 carrier is operated step by step by a pawl 73, Figs. 6 and 10 on an arm 74 engaging teeth 75 on the depending skirt 76 of the carrier. The arm 74 is operated as herein-after described. The platform or table 71 30 has an opening 77 therein through which a plunger 78" rises at intervals to lift the bottles to the syrup pump and the filling and capping head. The plunger as shown in Fig. 6 is operated from a revolving cam 79 35 on the vertical shaft 24 which is driven by worm gearing 81, 82".

This shaft at its upper end is connected through bevel gearing with the horizontal shaft 41 which has the cam 40 mounted 40 thereon, said shaft also having thereon the agitator in the cap hopper 8 and the cam portions 22, 23.

The dial or carrier 70 is circular, but is arranged eccentric to the vertical shaft 24 so 45 that its bottle holding pockets at the point where the bottles are placed or removed by the attendant will be farther from the shaft than they are when under the capping head. This will enable the attendant to place and 50 remove bottles readily without interference by the overhanging parts of the superstructure. This arrangement is shown in Fig. 6 in which it will be observed the bottle at the 55 right of the figure, that is, at the feeding point, is farther from the center of the machine than the bottle at the left of said figure, thus bringing the feeding point well out from under the overhanging upper structure of the machine.

60 The arm 74 which carries the pawl 73' is mounted on a vertical rock shaft 80 dotted lines, Fig. 6, said rock shaft being operated by an arm 83 at its lower end which, in turn, is operated from the cam 84 on the vertical 65 shaft 24.

In Fig. 5 the dial is shown as concentric with the vertical shaft but as indicated in Fig. 6 I prefer to make this dial eccentric to said shaft.

For holding the gasket controlling ring 20 70 various means may be employed. For instance, I show in Fig. 7 a clamp ring 85 which embraces the ring 20. This clamping ring is held to a fixed part of the machine by the lug 86. By loosening the screw or 75 bolt 87 the ring 20 can be adjusted circumferentially and then by tightening up on the bolt the clamping ring will hold the gasket controlling ring 20 against circumferential movement. Vertical movement however, 80 can take place by the lug 86 moving between the lugs 87 of the fixed frame part.

In Fig. 6 I show shells 70" in the dial or rotary carrier to receive the bottles. These shells have ribs or flanges bearing against 85 the walls of the openings in the dials by which they are centered and guided in their vertical movements. The shells may be of different diameter to suit different sizes (diameters) of bottles. They are of course 90 removable so that they can be replaced with shells of different sizes. The same dial can therefore accommodate different diameters of bottles by the use of the shells.

It will be understood from the above that 95 I have provided means to be located within the bottle for throttling the pressure of the inflowing liquid for the purpose of avoiding foaming, said throttling means having such form that the stream of water is broken up 100 or separated before striking the walls of the bottle and before mingling with the syrup. This device is referred to as a throttling means in the sense that it prevents the gas charged liquid from striking the bottle or 105 the syrup contained therein with full force which would induce foaming to a high degree and also in the sense that the stream of liquid is broken up into separate particles or portions lacking the pressure or force of 110 the original stream. In other words, when the gas charged liquid comes in contact with the syrup its force has been practically spent. Further, it will be understood that by spreading the liquid laterally and breaking it up, or separating it into different portions or particles the escape of the air from within the bottle is provided for because of the spaces within the bottle not fully occupied by the laterally directed portions of the 115 liquid.

What I claim is:—

1. In combination in a bottling machine, a capping head having a capping tool and a cap port, a cap chute leading to said head, a pad block for closing the cap port, said capping head being movable to carry the cap port from position where it is sealed by the pad block to a position in registry with the cap chute and to carry said port with its 125 130

newly fed cap back to the position first mentioned, substantially as described.

2. In combination in a bottling machine, a capping head having a capping tool and a cap port, a cap chute leading to said head, a pad block for closing the cap port, said capping head being movable to carry the cap port from position where it is sealed by the pad block to a position in registry with the cap chute and to carry said port with its newly fed cap back to the position first mentioned, said cap chute being fixed and the head acting as a cut off for the caps in said chute, substantially as described.

15 3. In combination in a bottling machine, a capping head having a capping tool and a cap port, a cap chute leading to said head, a pad block for closing the cap port, said capping head being movable to carry the cap port from position where it is sealed by the pad block to a position in registry with the cap chute and to carry said port with its newly fed cap back to the position first mentioned, said pad block being movable to and from the position for sealing the cap port, substantially as described.

4. In combination in a bottling machine, a capping head having a capping tool and a cap port, a cap chute leading to said head, a pad block for closing the cap port, said capping head being movable to carry the cap port from position where it is sealed by the pad block to a position in registry with the cap chute and to carry said port with its newly fed cap back to the position first mentioned, said pad block being movable to and from the position for sealing the cap port, and a member common to the capping head and pad block for turning the former and moving the latter, substantially as described.

5. In combination in a bottling machine, a capping head having a capping tool and a cap port, a cap chute leading to said head, a pad block for closing the cap port, said capping head being movable to carry the cap port from position where it is sealed by the pad block to a position in registry with the cap chute and to carry said port with its newly fed cap back to the position first mentioned, said pad block being movable to and from the position for sealing the cap port and a member common to the capping head and pad block for shifting the former and moving the latter, said member consisting of a lever to engage the capping head and carrying the pad block, substantially as described.

6. In combination in a bottling machine, a capping head having a capping tool thereon and a cap port, a pad block for sealing said port, a cap delivery chute, a yielding gasket for making a liquid and gas tight joint with the bottle, at the mouth of said head and means for moving the capping

head to carry its cap port from the position where it is sealed by the pad block to a position in registry with the cap chute to receive a cap therefrom and for returning the said head back to the position first mentioned, and compressing means for the gasket operated by the moving of the head to compress the gasket into sealing position when the head is sealed by the pad block, substantially as described.

7. In combination in a bottling machine, a capping head having a capping tool thereon and a cap port, a pad block for sealing said port, a cap delivery chute, a yielding gasket for making a liquid and gas tight joint with the bottle, at the mouth of said head and means for moving the capping head to carry its cap port from the position where it is sealed by the pad block to a position in registry with the cap chute to receive a cap therefrom and for returning the said head back to the position first mentioned, and compressing means for the gasket operated by the moving of the head to compress the gasket into sealing position when the head is sealed by the pad block, said means comprising a ring with a screw thread connection between the same and the head, substantially as described.

8. In combination a capping head having a capping tool, a filling tube passing through the head for delivering gas-charged liquid, and a liquid spreading device receiving the liquid at a point within the bottle and below the neck to deflect said liquid laterally against the wall of the bottle, said spreading device having a lateral discharge opening or openings occupying only a part of the circumference of said device to discharge the liquid at a certain point or points while leaving a space for the escape of the gas at another point or points around said device, substantially as described.

9. In combination, a capping head having a capping tool, a filling tube for delivering gas-charged liquid and a liquid spreading device receiving the liquid from the said tube at a point within the bottle below the neck to deflect said liquid laterally against the wall of the bottle, substantially as described.

10. In combination in a bottle filling machine, means for first introducing syrup into the bottle, a capping head having a capping tool, a filling tube for delivering gas-charged liquid into the bottle containing the syrup, a spreading device for receiving the liquid from the filling tube, and located within the bottle, said spreader directing the water laterally against the walls of the bottle, and means for breaking up the stream of water after leaving the spreader to fall upon the syrup in its broken up condition, substantially as described.

11. In combination in a bottle filling ma-

chine, means for first introducing syrup into the bottle, a capping head having a capping tool, a filling tube for delivering gas-charged liquid into the bottle containing the syrup, 5 and means for deflecting the gas-charged liquid laterally toward the wall of the bottle but breaking it up before reaching said wall, substantially as described.

12. In combination a capping head having 10 a capping tool, a filling tube, a spreader to receive the liquid from the filling tube and deflect it laterally, a tube over the spreader for dividing the oncoming stream from the liquid as deflected laterally by the said 15 spreader, substantially as described.

13. In combination, a capping head having a capping tool therein, a filling tube, means for first introducing syrup into the bottle and then introducing water through 20 the tube into said bottle and means for spreading the water at a point above the charge of syrup when in the bottle and outwardly against the walls of the bottle to thereby allow the liquid to settle on to the 25 syrup, substantially as described.

14. In combination in a bottling machine, means for filling water into the bottle, capping means and a syrup filling device consisting of a measuring chamber, a port leading 30 thereto, a member sliding over said port and having two passages, one connected with a syrup supply and the other with the bottle receiving mouth, said passages registering with the port alternately as the sliding member is moved, said sliding member being moved through contact with the bottle, 35 substantially as described.

15. In combination, a capping head having rotary movement, to and from a cap 40 chute, a pad block, means for turning the head and for moving the pad block, a vertical shaft from which said turning head and pad block are operated, a carrier for bottles, operated by said vertical shaft, means for 45 securing a vertical movement of the bottles, a filling tube vertically movable, means connected with the vertical shaft for operating said tube, a hopper, an agitator therein and means for driving said agitator from the 50 said vertical shaft, substantially as described.

16. In combination in a bottling machine, a capping head, filling valve mechanism, cap feeding and cap applying means, and a rotary dial having pockets for carrying the 55 bottles, a vertical shaft about which the dial turns, said dial being eccentric to the said vertical shaft to bring the bottle pockets at a maximum distance from the shaft at the 60 feeding point and out beyond the upper structure of the machine and at substantially the minimum distance from the shaft at the capping point, and means for operating the said dial, substantially as described.

17. In combination in a bottling machine,

means for filling water into the bottle, capping means and a syrup filling device consisting of a measuring chamber, a port leading thereto, a member sliding over said port and having two passages, one connected 70 with a syrup supply and the other with the bottle receiving mouth, said passages registering with the ports alternately as the sliding member is moved, substantially as described.

18. In combination, a rotary capping head having a cap port, a pad block for closing said port, a cap chute to supply caps, means for turning the head to make its port register with the cap chute and cap port alternately, a gasket for sealing the mouth of the head about the bottle, a gasket compressor ring, a connection between the head and ring for raising and lowering the latter as the head is turned, and means for holding the gasket compressor ring against turning said ring being adjustable circumferentially and in relation to said holding means, substantially as described.

19. In combination in a bottling machine, 90 a vertical shaft, a standard in which said shaft rotates, a bottle carrying dial rotatable about the said standard, a capping head supported by the standard, cap supplying means including a hopper supported on the 95 standard, liquid supplying means and connections for operating the same from the vertical shaft, substantially as described.

20. In combination in a bottling machine, 100 a vertical shaft, a standard in which said shaft rotates, a bottle carrying dial turnable about said standard, a capping head supported by the standard, cap supplying means including a hopper and an agitator within the same supported by said standard, 105 liquid supplying devices, and connections from the vertical shaft for operating the liquid supplying devices and for operating the agitator within the hopper, substantially as described.

21. In combination in a bottling machine, a vertical shaft, a standard in which said shaft rotates, a bottle carrying dial rotatable about the standard, a connection from the vertical shaft for rotating the dial, a capping head, cap supplying means, liquid supplying means, and connections for operating the liquid supplying means from the vertical shaft, substantially as described.

22. In combination in a bottling machine, 120 a vertical shaft, a vertical standard in which said shaft rotates, a capping tool, liquid supplying means, cap supplying means, and connections from the vertical shaft for controlling the feed of the liquid and caps, substantially as described.

23. In combination in a bottling machine, 125 a vertical shaft, a vertical standard in which said shaft rotates, a capping tool, liquid supplying means, cap supplying means, in-

- cluding a hopper and a chute, supported from the standard, and connections from the vertical shaft for controlling the liquid supplying means and for controlling the delivery of the caps from the chute, substantially as described.
24. In combination in a bottling machine, a vertical shaft, a vertical standard in which said shaft rotates, a capping head, liquid supplying means, cap supplying means including a hopper, and an agitator therein, a horizontal shaft at the top of the vertical shaft, means for driving the horizontal shaft from the vertical shaft, and connections for operating the liquid supplying means from the horizontal shaft, said horizontal shaft operating the agitator, substantially as described.
25. In combination in a bottling machine, a vertical shaft, a standard in which said shaft rotates, a bottle carrying dial turnable about said standard, means for operating said dial step by step, liquid supplying mechanism, cap supplying mechanism, cap applying mechanism, all of said mechanism being controlled from the vertical shaft, substantially as described.
26. In combination in a bottling machine, a vertical shaft, a standard in which said shaft rotates, a capping head supported by said standard, a cap hopper supported by said standard, liquid supplying means operated from the vertical shaft, a vertically movable plunger for raising the bottle for capping, and a cam on the vertical shaft for operating the said plunger, substantially as described.
27. In combination in a bottling machine, a vertical shaft, a standard in which said shaft rotates, a capping head supported by the standard, a rotary bottle carrier turnable about the standard, a plunger operating vertically to raise the bottle to the capping head, liquid supplying means operated from the vertical shaft, a cam on the vertical shaft for operating the vertical plunger, and a cam on the vertical shaft with connections to the rotary bottle carrier for operating it, substantially as described.
28. In combination in a bottling machine, a vertical shaft, a standard in which the shaft rotates, a capping head and cap hopper supported on the upper end of the standard, a capping tool, a bottle carrier rotatable about the standard, means for effecting a relative movement vertically between the bottle and capping tool operated from the lower part of the shaft, means for rotat-
- ing the bottle carrier from the lower part of the shaft, liquid supplying means, and connections from the upper part of the vertical shaft for controlling the liquid supplying means and for controlling the delivery of caps, substantially as described.
29. In combination in a bottling machine, a vertical shaft, means for driving the same, a standard in which said shaft turns, bottle filling and capping means at the upper end of said standard, a bottle carrier rotating about the standard, connections between the upper part of the vertical shaft and the bottle filling means for operating the same, cap supplying means, connections from the upper part of the vertical shaft for controlling the same, a connection for effecting a relative movement between the bottle and capping means, a connection for rotating the bottle carrier, and means at the lower part of the shaft for operating the said connections, said standard having a hood at its lower part inclosing the said means, substantially as described.
30. In combination in a bottling machine, a bottle support, a vertical shaft, a vertical standard in which said shaft rotates, a capping head having a cap port, liquid supplying means, cap supplying means including a hopper with an agitator therein and a chute leading to the capping head, a pad block for closing the cap port, means operated from the vertical shaft for effecting relative movement between the chute, capping head and pad block to effect the delivery of caps to the capping head and the sealing of said head, a horizontal shaft at the upper end of the vertical shaft geared thereto, and connections for operating the liquid supplying devices from said horizontal shaft, substantially as described.
31. In combination with a filling head, a filling tube having near its lower end a lateral discharge opening for the liquid extending vertically of the wall thereof to secure a lateral discharge of the liquid at different levels, a spreader at the lower end of the tube, and means for delivering a restricted stream of liquid onto said spreader, said means being of a diameter less than that of the inner diameter of the tube at the level of said openings.

In testimony whereof, I affix my signature in presence of two witnesses.

ALBERT ALFRED CARPER.

Witnesses:

WALTER DONALDSON,
BENNETT S. JONES.
